UNITED STATES PATENT OFFICE

FRED W. SCHMIDT AND WILLIAM B. THORNTON, OF PHILADELPHIA, PENNSYLVANIA

EXHAUST NOZZLE

Application filed January 29, 1929. Serial No. 335,912.

This invention is adapted for use on a four-cylinder high pressure locomotive engine, in which two cylinders are located at the forward end of the locomotive and two located some distance in the rear of the forward cylinders. The invention is particularly adapted to a simple "Mallet" four-cylinder high pressure engine.

One object of the invention is to provide separate nozzles for the forward and rear cylinders, and to have a common chamber for the bleeding of exhaust steam from the nozzles, for the purpose of supplying steam to an exhaust steam feed water heater.

15 In the accompanying drawing:

Fig. 1 is a side view, partly in section, illustrating our improved exhaust nozzle structure;

Fig. 2 is a sectional plan view on the line 20 2—2, Fig. 1;

Fig. 3 is an end view; and

Fig. 4 is a sectional view on the line 4—4, Fig. 1.

Referring to the drawing, 1 is the exhaust nozzle of the forward cylinders, and 2 is the nozzle for the rear cylinders in the present instance. Connecting the two nozzles is a casing 3, enclosing a chamber which communicates with both nozzles through ports 4 and 5, respectively, in the casings of the nozzles 1 and 2.

The casing 3 terminates in a pipe 6 having a flange 7 coupled to a pipe leading to a feed water heater. The casing is so shaped that exhaust steam can readily flow from the nozzles into said chamber and pass to the feed water heater.

The nozzle 1 has a flange 8 which is coupled to a pipe leading from the forward cylinders of the locomotive.

The nozzle 2 has two necks 9—9, each neck having a flange 10 to which the pipes leading from the rear cylinders of the locomotive are coupled.

45 A foot 11 is located under the nozzle 2. This foot is secured to the bottom of the smoke-box.

The upper end of each nozzle is shaped to 50 receive the usual nozzle extension tip. These

nozzles may discharge into a single stack or two stacks arranged one back of the other if desired.

The structure is preferably made in a single casting but it may be made in two parts 55 coupled together if desired.

Due to the back pressure on the exhaust steam and the partial vacuum formed by the condensation of the exhaust steam in the feed water heater, a head is formed, causing a 60 certain amount of steam to flow towards the feed water heater after collecting in the common chamber in the casing 3. Such exhaust steam that is not collected in the chamber passes to the atmosphere by way of the 65 stack or stacks from the nozzles 1 and 2.

We claim:

1. In an exhaust nozzle structure, the combination of two nozzles; and a chamber arranged to conduct exhaust steam to a feed 70 water heater, each of said nozzles having ports communicating with said chamber.

2. The combination of two nozzles arranged side-by-side and connected to different cylinders; and a casing encircling both 75 nozzles and having a chamber therein, each of said nozzles having ports communicating with the chamber.

3. A nozzle structure for a four-cylinder locomotive, consisting of two nozzles, one 80 nozzle for one set of cylinders, and the other nozzle for the other set of cylinders.

4. A nozzle structure for a four-cylinder locomotive, consisting of two nozzles arranged one back of the other and formed as an integral casting.

5. A nozzle structure for a four-cylinder engine, consisting of two nozzles arranged close together; a casing enclosing a portion of each nozzle; and a port in each nozzle 90 communicating with the chamber formed by the casing, said casing being arranged to be coupled to a pipe leading to a feed water heater, one of said nozzles having lateral tubular extensions coupled to exhaust pipes. 95
